UNITED STATES PATENT OFFICE

2,112,049

AIR CONDITIONING SYSTEM

Edward W. Roessler, Nutley, N. J., assignor to
 General Electric Company, a corporation of
 New York

Application May 5, 1936, Serial No. 77,949

11 Claims. (Cl. 62—6)

My invention relates to systems for conditioning the air within auditoriums, rooms and other enclosures, and particularly to systems for cooling air and which include both temperature and 5 humidity regulation.

During the summer months, when it is necessary to cool the air circulated through auditoriums, rooms and other enclosures in order to maintain the proper temperatures for maximum 10 comfort, it is frequently desirable to use only a portion of the cooling surface available in a cooling coil. In such systems the cooling coil is utilized both to cool the air and to abstract moisture therefrom; the moisture which condenses on 15 the cooling coil is collected and removed in any suitable manner. When the relative humidity of the air within a room is high, it may happen that the operation of the cooling coil will reduce the temperature of the air sufficiently to satisfy the 20 requirements of the room thermostat before sufficient moisture has been abstracted from the air to satisfy the requirements of the room humidostat. In other words, it is desirable further to reduce the humidity after the temperature has 25 been reduced to the desired value.

Accordingly, it is an object of my invention to provide an improved system for conditioning the air within an enclosure including a cooling coil and an arrangement for varying the effective 20 cooling surface of the coil dependent upon the temperature and humidity of the air in the enclosure.

Another object of my invention is to provide a system for cooling and dehumidifying the air 35 within an enclosure including a cooling coil and an improved arrangement dependent upon the temperature and humidity of the air in the enclosure for varying the length of the portion of the coil containing superheated refrigerant 40 vapor.

A further object of my invention is to provide a system for cooling the air within an enclosure including a cooling coil having a valve controlling the supply of cooling medium in response to the 45 outlet temperature of the coil for maintaining a predetermined temperature of the cooling medium withdrawn from the coil and a device responsive to a condition of the air in the enclosure for modifying the operation of the valve to maintain a different predetermined temperature of the medium withdrawn from the coil.

Further objects and advantages of my invention will become apparent as the following description proceeds and the features of novelty 55 which characterize my invention will be pointed

out with particularity in the claims annexed to and forming a part of this specification.

For better understanding of my invention, reference may be had to the accompanying drawing, the single figure of which shows diagrammatically an air conditioning system embodying 5 my invention.

Referring now to the drawing, I have shown an air conditioning system comprising a casing 10 arranged to receive air from a room or enclosure 10 to be conditioned through a duct 11 opening into the room through a wall 9 and to receive fresh air from outside the room through a duct 12. Dampers 13 and 14 are provided in the ducts 11 and 12, respectively, to control the amounts of fresh 15 and room air admitted to the casing 10. The fresh and room air mix in the casing 10 and the mixture passes through a filter 15 and a cooling element 16 where the temperature and humidity thereof are reduced. The fresh air and the room 20 air are drawn into the casing 10 by operation of a fan or blower 17 and the conditioned air is discharged into the room through a duct 18 passing through the wall 9.

The cooling element 16 comprises a sinuous coil 25 19 having a plurality of turns arranged in three banks 19a, 19b, and 19c, each extending entirely across the casing 10 in the path of the air to be conditioned. This coil may be of any desired 30 construction and is preferably of the type provided with a plurality of fins to increase the effective surface area thereof. Coil 19 is connected in the circuit of a mechanical refrigerating machine comprising a compressor 20, driven by an electric 35 motor 21, which receives vaporized refrigerant from the coil 19 through a conduit 22, compresses the refrigerant, and delivers the compressed refrigerant through a conduit 23 to a condenser 24. The compressed refrigerant in the condenser 24 is cooled and liquefied by air circulated thereover 40 by a fan 25 driven by an electric motor 26 connected across the motor 21. The liquid refrigerant flows into a receiver 27 and thence through an expansion valve 28 and a connection 29 to the coil 19. The refrigerant is preferably admitted 45 to the coil so that it flows through the banks of the coil in succession in the opposite direction from that of the flow of air through the duct 10. The air thus passes progressively from the least cold to the coldest bank of the coil. 50

The expansion valve 28 is of the thermostatically operated type well known in the art, it being operated in response to the temperature of the refrigerant withdrawn from the evaporator coil 19. When a vaporizable refrigerant is employed, 55

a valve of this type may be set to maintain superheated the refrigerant vapor in any predetermined length of the cooling coil. The valve 28 comprises a casing 30 divided by a partition 31 into an entrance chamber 32 and an outlet chamber 33. A valve 34 arranged to seat in an opening 35 in the partition 31 controls the passage of refrigerant from the inlet chamber 32 to the outlet chamber 33. In order to provide thermostatic control of the valve 34, a diaphragm 31a of the bellows type is sealed in the casing 30 to form a third chamber 36 at the end of the casing 28 remote from the inlet chamber. The valve 34 which is mounted on a rod 31 is biased toward its closed position by a spring 38 and the force of the spring is opposed by the pressure of vapor in the chamber 36. A bulb 39 containing a volatile liquid is secured adjacent the suction side of the coil 19 and determines the vapor pressure in the chamber 36 to which it is connected by a tube 40; the pressure being varied in accordance with the temperature of the vapor withdrawn from the coil 19. An increase of the temperature of the vapor being withdrawn from the coil 19 will vaporize some of the liquid in the bulb 39 and increase the pressure in the chamber 36. This increase in pressure opposes the force of the spring 38 and opens the valve 34, thereby admitting refrigerant to the coil 19. The operation of the expansion valve 28 maintains a predetermined substantially constant temperature of the refrigerant withdrawn from the coil 19.

During normal operation of the cooling system shown, the temperature of the air in the room is regulated by a thermostat 41 located in the room. This thermostat operates to control the connection between the motor 21 and power supply lines 42 and 43 and thereby determines the periods during which the compressor 20 shall operate to supply refrigerant to the coil 19. The fan 25 is operated only when the refrigerating machine is being operated.

The thermostat 41 comprises a bimetallic strip 44 arranged to make contact with either one of two stationary contacts 45 and 46 depending upon the variation of the temperature in the room to be conditioned. When the temperature of the air in the room rises to a predetermined maximum value, the strip 44 touches the contact 46 and closes a circuit from one side of a secondary coil 47 of a transformer 48 through a line 49, the strip 44, a connection 50, to a coil 51 of a solenoid switch 52, and thence through a connection 53 and a line 54 to the other side of the secondary coil 47. Coil 51 is thereby energized and raises an armature 55 of the switch 52 thereby raising two switch arms 56 and 57 to engage stationary contacts 58 and 59, respectively. The engagement of the switch arm 56 with the contact 58 closes a circuit including a connection 60, switch arm 56, contact 58 and a connection 61, establishing a by-pass around the bimetallic strip 44 and closing a holding circuit to maintain coil 51 energized from the transformer 48 even though the strip 44 should move away from the contact 46. The closing of the upper switch arm 57 establishes a circuit from the line 42 through a line 62, a connection 63, contact 59, arm 57, and a line 64 to a coil 65 of a switch 66 and thence through a line 67 to line 43. Energization of coil 65 raises an armature 68 of the switch 66 and closes the switch, thereby connecting lines 62 and 67 to leads 69 and 70, respectively, of motor 21 to start the motor and drive the compressor 20. The fan motor 26 is connected across the leads 69 and 70,

so that it is energized concurrently with the compressor motor.

The motor 21 will continue to operate and the refrigerating machine will supply refrigerant to the coil 19 until the temperature of the air within the room to be conditioned has been decreased to a predetermined value whereupon the bimetallic strip 44 will engage the contact 45 and short-circuit the coil 51 through connection 50, strip 44, a connection 11 and connection 53. The 10 armature 55 then falls into the position shown in the drawing and the arms 56 and 57 break contact with the contacts 58 and 59, respectively; this opens the circuit of coil 65, causing armature 68 to drop out and disconnect the motor 21 from 15 the lines 62 and 67 to stop the operation of the compressor 20 and the fan 25. It will be noted that the arm 56 of the switch 52 in its drop-out position engages a contact 72, the purpose of which will be hereinafter set forth. 20

When the humidity of the air in the room to be conditioned is high, it may happen that the thermostat 41 will be satisfied and will operate to stop the motor 21 before the humidity has been lowered sufficiently for comfort. It may be desirable in such a case to continue the operation of the coil 19 at a reduced rate to remove further moisture from the air without greatly decreasing the temperature of the air passing through the duct. I, therefore, provide an arrangement to 30 modify the operation of the expansion valve and restrict the supply of refrigerant to the coil in the event that the humidity of the air in the room is still too high after the room thermostat has been satisfied. When the supply of refrigerant is thus restricted an increased percentage of the total coil length is filled with superheated refrigerant gas and the gas is withdrawn from the coil at a higher temperature. With the refrigerant flow restricted in this manner, the balance 35 of heat transfer capacity between the coil and the compressor is changed so that a lower refrigerant pressure is maintained in the coil. The saturation temperature of the refrigerant is lower at the lower pressure, and the surface temperature of the coil is, therefore, lower in that portion of the coil in which the gas is not superheated. The dehumidification accomplished by this cold portion of the coil is increased as compared with dehumidification during the normal 40 operation of that portion, but the total sensible heat removed by the coil from the air is reduced. I arrange the device for modifying the operation of the expansion valve so that it is controlled 45 in response to the humidity of the air in the enclosure to be conditioned. 50

The arrangement for modifying the operation of the expansion valve 28 comprises an expansible chamber or bellows 73 in communication with the valve operating chamber 36 through a tube 74. 60 By varying the volume of this second chamber the pressure in the chamber 36 is varied and, consequently, a different temperature of the bulb 39 will be required to produce the same movement of the valve. When the chamber 73 is compressed, a certain predetermined temperature of the bulb 39 will open the valve 34 and when the chamber 73 is expanded a higher temperature of the bulb is required to open the valve, for normal operation of the system in response to the 65 thermostat 41 the chamber 73 is held compressed and a minimum length of the coil 19 is maintained filled with superheated gaseous refrigerant. When only a portion of the coil 19 is to be used for cooling and dehumidifying the air, the 70 75

chamber 73 is allowed to expand, whereupon a greater length of the coil 19 is maintained filled with superheated gaseous refrigerant.

Any suitable arrangement may be provided for varying the volume of the bellows 73. In the construction illustrated, I have shown a second bellows 75 filled with air or other gas mounted in a casing 76 with the bellows 73 and connected at one end to the bellows 73 through a rigid member 77. The maximum volume of the bellows 73 is limited by a stop 78 formed in the walls of the casing 76 and the bellows 73 is biased to its expanded position by a compression spring 79. In order to compress the bellows 73, I provide a heating element 80 within the bellows 75 and energize the heating element to expand the air or other gas within the bellows 75. Whenever the thermostat 41 operates to start the motor 21 the circuit of the heater 80 is closed. This circuit may be traced from the line 62, through switch arm 57, a line 81, an arm 82 of a solenoid switch 83 and a contact 84, to a line 85, and through heating element 80 and a connection 86 to line 43. Whenever the motor 21 is energized in response to operation of thermostat 41 the heating element is energized to compress bellows 73 and increase the pressure in the chamber 36 so that the thermostatic expansion valve 28 maintains a minimum temperature of the refrigerant withdrawn from the coil 19; that is, so that a minimum length of the coil 19 contains superheated vapor.

In order to maintain the desired humidity of the air in the room to be conditioned, I provide a humidostat 87. The humidostat 87 is arranged to operate the motor 21 and continue the operation of the compressor 20 in the event that the humidity of the air in the enclosure is too high after the temperature conditions determined by the thermostat 41 have been satisfied. The humidostat 87 has no effect on the operation of the system unless the switch 52 operated by the thermostat 41 is in its drop-out position. In other words, control of the refrigerating machine in response to the room thermostat takes precedence over the control by the humidostat.

Should the humidity be too high after the minimum temperature determined by the thermostat 41 has been reached, a movable member 88 of humidostat 87 will be in engagement with a contact 89 and close a circuit from the secondary 47 of the transformer through arm 56 and contact 72, lines 90 and 91, member 88, a connection 92, a contact 93, a bimetallic strip 94, and a connection 95, to a coil 96 of the switch 83, and thence back to the secondary 47 through a line 91. The energization of the coil 96 raises a solenoid 98 of the switch 83 to lift arms 82 and 99 of the switch into engagement with contacts 100 and 101, respectively. The engagement of arm 99 with contact 101 establishes a holding circuit for the coil 96 through a connection 102 to the line 90. The engagement of arm 82 with contact 100 closes a circuit from line 42 through a line 103, arm 82, connection 81 and line 64, to coil 65 and to line 43 through line 67, thereby energizing the coil 65 and closing the motor operating switch 66. Furthermore, when the arm 82 is raised, the circuit of the heating element 80 is broken and the bellows 73 expands and modifies the operation of the thermostatic expansion valve 28 to maintain the refrigerant withdrawn from the coil 19 at a higher temperature, as has been explained above. A major portion of the length of the

coil 19 is then maintained filled with superheated refrigerant vapor and a minimum length of the coil 19 is maintained at low temperature to abstract moisture from the air. Dehumidification of the air is thus continued with less cooling of the total volume of air circulated through the casing 10.

When the humidity is sufficiently low, the member 88 of the humidostat 87 will engage a contact 104 to short-circuit the coil 96 through a connection 105 and thereby cause the armature 98 to drop out and de-energize the coil 65 to stop the motor 21.

When the humidity of the air is extremely high, it may not be reduced sufficiently to satisfy the humidostat 87 before the temperature of the air becomes too low to be comfortable for the occupants of the room. In order to prevent excessive cooling of the air I provide a limit thermostat 106 responsive to room temperature. This thermostat comprises the bimetallic strip 94, the contact 93, and a second contact 107. The bimetallic strip 94 normally engages the contact 93. However, should the temperature of the air reach a predetermined minimum, which is the lowest temperature consistent with comfort, strip 94 will engage contact 107, short-circuiting the coil 96 through a connection 108 to open switch 83 and discontinue operation of the motor 21.

It is probable that in the majority of air conditioning installations a substantial amount of heat is supplied to the enclosure to be conditioned from sources within that enclosure. For example, electric lights, motors, and other heat producing devices are often present in the room and heat is also produced in the room by the sun's rays entering through windows. It is necessary that the heat from these internal sources be removed from the room before any temperature reduction below the temperature of the outdoor air can take place. In other words, a part of the capacity of the cooling system serves merely to overcome heat generated within the enclosure. Obviously, then a continuous circulation of a small amount of cooled air may be maintained without reducing the temperature of the air in the room; this circulation serving merely to balance the effect of the heat generated in the room. In the system which I have described above, it is possible to produce a substantial amount of dehumidification with only sufficient sensible cooling of the air circulated through the conditioner to offset the effect of the internal heat sources in the room and thus there results no reduction of the dry bulb temperature of the air in the room. It is apparent, therefore, that the low temperature limit thermostat would be operated only in rare cases.

It will be apparent from the foregoing that I have provided an air conditioning system including a simple and effective arrangement for regulating the temperature and humidity of an enclosure to be cooled, which makes possible the independent regulation of humidity after the room thermostat has been satisfied.

While I have disclosed a particular embodiment of my invention, various modifications will occur to those skilled in the art. I do not, therefore, desire my invention to be limited to the construction shown and described and I intend in the appended claims to cover all modifications thereof which do not depart from the spirit and scope of my invention.

What I claim as new and desire to secure by Letters Patent of the United States is:

1. A system for conditioning the air within an enclosure including a duct communicating with said enclosure, a cooling coil arranged in said duct, means for supplying cooling medium to said coil and for withdrawing said medium from said coil, means responsive to the temperature of the medium withdrawn from said coil for maintaining a predetermined substantially constant temperature of said withdrawn medium, and means responsive to the humidity of the air in said enclosure and modifying the operation of said last-mentioned means for maintaining a predetermined different substantially constant temperature of said withdrawn medium.
2. A system for conditioning the air within an enclosure including a cooling coil, means for supplying liquid refrigerant to said coil and for withdrawing gaseous refrigerant from said coil, means responsive to the temperature of the refrigerant withdrawn from said coil for maintaining superheated the gaseous refrigerant in a predetermined length of said coil, and means responsive to the humidity of the air in said enclosure and modifying the operation of said last-mentioned means for maintaining superheated the gaseous refrigerant in a different predetermined length of said coil.
3. A system for conditioning the air within an enclosure including a duct communicating with said enclosure, a cooling coil arranged across said duct, means for supplying liquid refrigerant to said coil and for withdrawing gaseous refrigerant from said coil, means responsive to the temperature of the refrigerant withdrawn from said coil for maintaining superheated the gaseous refrigerant in a predetermined length of said coil, and means responsive to the humidity of the air in said enclosure and modifying the operation of said last-mentioned means for maintaining superheated the gaseous refrigerant in a shorter predetermined length of said coil.
4. A system for conditioning the air within an enclosure including a cooling coil, means for supplying cooling medium to said coil and for withdrawing cooling medium from said coil, means including a valve for controlling the supply of cooling medium to said coil, means responsive to the temperature of cooling medium withdrawn from said coil and actuating said valve for maintaining a predetermined substantially constant temperature of the cooling medium withdrawn from said coil, and means responsive to the humidity of the air in said enclosure and modifying the operation of said last-mentioned means for maintaining a different predetermined temperature of the cooling medium withdrawn from said coil.
5. A system for conditioning the air within an enclosure including a cooling coil, means for supplying cooling medium to said coil and for withdrawing cooling medium from said coil, means including a valve for controlling the supply of cooling medium to said coil, means responsive to the temperature of cooling medium withdrawn from said coil and actuating said valve for maintaining a predetermined substantially constant temperature of the cooling medium withdrawn from said coil, means responsive to the humidity of the air in said enclosure and modifying the operation of said last-mentioned means for maintaining a different predetermined temperature of the cooling medium withdrawn from said coil, and means dependent upon a predetermined minimum temperature of the air within said enclosure for rendering said humidity responsive means ineffective.
6. A system for conditioning the air within an enclosure including a cooling coil, means for supplying cooling medium to said coil and for withdrawing cooling medium from said coil, means including a valve for controlling the supply of the cooling medium to said coil, means responsive to the temperature of the cooling medium withdrawn from said coil and including an expandable chamber and a bulb filled with a volatile liquid and communicating with said chamber for actuating said valve to maintain a predetermined substantially constant temperature of the cooling medium withdrawn from said coil, and means responsive to the humidity of the air in said enclosure and modifying the operation of said last-mentioned means by changing the pressure within said expandable chamber for maintaining a different predetermined temperature of the cooling medium withdrawn from said coil.
7. A system for conditioning the air within an enclosure including a cooling coil, means for supplying cooling medium to said coil and for withdrawing cooling medium from said coil, means including a valve for controlling the supply of the cooling medium to said coil, means responsive to the temperature of the cooling medium withdrawn from said coil and including an expandable chamber and a bulb filled with a volatile liquid and communicating with said chamber for actuating said valve to maintain a predetermined substantially constant temperature of the cooling medium withdrawn from said coil, means providing a second expandable chamber in communication with said first chamber, and means responsive to the humidity of the air in said enclosure and modifying the operation of said valve actuating means by changing the volume of said second chamber for maintaining a different predetermined temperature of the cooling medium withdrawn from said coil.
8. A system for conditioning the air within an enclosure including a cooling coil, means for supplying cooling medium to said coil and for withdrawing cooling medium from said coil, means including a valve for controlling the supply of the cooling medium to said coil, means responsive to the temperature of the cooling medium withdrawn from said coil and including an expandable chamber and a bulb filled with a volatile liquid communicating with said chamber for actuating said valve to maintain a predetermined substantially constant temperature of the cooling medium withdrawn from said coil, means for providing a second expandable chamber in communication with said first chamber, a heating element arranged within said second chamber, means for energizing said heating element, and means responsive to the humidity of the air in said enclosure and varying the energization of said heating element to modify the operation of said valve actuating means by changing the volume of said second chamber for maintaining a different predetermined temperature of the cooling medium withdrawn from said coil.
9. A system for conditioning the air within an enclosure including a cooling coil, means for supplying cooling medium to said coil and for withdrawing cooling medium from said coil, means including a valve for controlling the supply of cooling medium to said coil, means responsive to the temperature of the cooling medium withdrawn from said coil and including an expandable chamber and a bulb filled with a volatile liquid.

tile liquid and communicating with said chamber and actuating said valve for maintaining a predetermined substantially constant temperature of the cooling medium withdrawn from said coil, 5 means for providing a second expansible chamber in communication with said first chamber, a heating element arranged within said second chamber, means dependent upon a predetermined maximum temperature of the air within said 10 enclosure for energizing said heating element, and means responsive to the humidity of the air in said enclosure and maintaining said heating element de-energized to reduce the volume of said second chamber and modifying the operation 15 of said valve actuating means for maintaining a different predetermined temperature of the cooling medium withdrawn from said coil.

10. A system for conditioning the air within an enclosure including a cooling element, means for supplying cooling medium to said element and for withdrawing said medium from said element, means dependent upon a predetermined maximum temperature of the air within said enclosure for actuating said cooling medium supplying 20 means, means responsive to the temperature of the cooling medium withdrawn from said element and operable within a predetermined range of temperatures below said maximum temperature for maintaining a predetermined substantially 25 constant temperature of said withdrawn medium during the operation of said cooling medium supplying means, and means responsive to the humidity of the air in said enclosure and actuating said cooling medium supplying means and modifying the operation of said temperature 30 maintaining means for maintaining a predetermined different substantially constant temperature of said withdrawn medium during operation of said cooling medium supplying means, and means dependent upon a predetermined minimum temperature of the air within 35 said enclosure for rendering said humidity responsive means ineffective and for stopping the operation of said cooling medium supplying means.

ture of said withdrawn medium during operation of said cooling medium supplying means, and means dependent upon a temperature in said enclosure below said predetermined range of temperatures for rendering ineffective said humidity responsive means. 5

11. A system for conditioning the air within an enclosure including a cooling element, means for supplying cooling medium to said element and for withdrawing said medium from said element, 10 means dependent upon a predetermined maximum temperature of the air within said enclosure for actuating said cooling medium supplying means, means responsive to the temperature of the cooling medium withdrawn from said element 15 and operable within a predetermined range of temperatures below said maximum temperature for maintaining a predetermined substantially constant temperature of said withdrawn medium during the operation of said cooling medium supplying means, means responsive to the humidity of the air in said enclosure and operable when the temperature of said air is below said range of temperatures to actuate said cooling medium supplying means and modifying the operation of 20 said temperature maintaining means for maintaining a predetermined different substantially constant temperature of said withdrawn medium during operation of said cooling medium supplying means, and means dependent upon a predetermined minimum temperature of the air within 25 said enclosure for rendering said humidity responsive means ineffective and for stopping the operation of said cooling medium supplying means. 30
